CHEST OR SIMILAR ARTICLE OF FURNITURE

John O. Van Koert, New York, N. Y., assignor to Drexel
Furniture Company, Drexel, N. C., a corporation of Delaware

Application August 2, 1955, Serial No. 37,264

Term of patent 14 years

(Cl. D33—6)

Fig. 1.

Fig. 2.

The back of the chest (not shown) is plain.

I claim:

The ornamental design for a chest or similar article of furniture, as shown and described.
